OTHER PUBLICATIONS

U.S. Appl. No. 15/889,134, filed Feb. 5, 2018, entitled "Printing Apparatus".

Primary Examiner — Susan B Hattan

Assistant Examiner — Leanne D Was-Englehart

(74) *Attorney, Agent, or Firm* — Fish & Richardson P.C.

(57) **CLAIM**

The ornamental design for a distance measuring guide for printer, substantially as shown and described.

DESCRIPTION

FIG. 1 is a bottom view of the distance measuring guide. FIG. 2 is a front view of the distance measuring guide. FIG. 3 is a front side perspective view of the distance measuring guide.

FIG. 4 is a back side perspective view of the distance measuring guide.

FIG. 5 is a back view of the distance measuring guide.

FIG. 6 is a side view of the distance measuring guide; and, FIG. 7 is a top view of the distance measuring guide.

1 Claim, 7 Drawing Sheets
